WIRE TWISTING TOOL

Theodore D. Baker, Seattle, Wash.

Application December 28, 1935, Serial No. 56,566

3 Claims. (Cl. 140—118)

My invention relates to tools for use in twisting the form wires used in holding together concrete forms.

It is necessary in the erection of concrete forms to twist together the wires extending from one side of the other of the form, to draw these sides of the form together to the proper distance, and to hold them against separation. This is generally done by twisting the ends of the wires together, first by hand at one side of the form, then with pliers tightening the wires as much as possible, which is still insufficient, and then reaching between the two sides of the form with a pair of pliers and engaging the handle of the pliers between the two strands of the wire, twisting them together until they have been drawn sufficiently tight. This is inherently a time consuming job, and the more so as the workman must reach into a comparatively narrow space where wire ends, nails, reinforcing steel, splinters, and other obstructions are liable to be encountered, and where he may scratch his hands or lose his tool. To obviate these difficulties it has been heretofore proposed to employ tools to engage the ends of the wire at one side of the form, and to twist them, and to pull them through, but all such tools, so far as I am aware, require insertion of the ends of the wires into apertures, or their careful positioning in the tool, with the result that time is lost in the engagement, and more particularly in the disengagement of the wire after the twisting operation is completed. These tools are further objectionable in that the two ends of the wire, bent about the stud at the opposite side of the form, and then simultaneously grasped by the tool, may be and usually are of uneven length, but will bite into the stud and resist pulling around evenly, and hence are unevenly tensioned. When twisted they may slip, one end relative to the other, or in trying to pull the form together one end of the wire may be so twisted and tensioned that then or later it breaks. Moreover, such tools, so far as I have any knowledge, are comparatively clumsy and expensive.

It is an object of the present invention, therefore, to provide a tool which is simple, yet strong and rugged, and one which is inexpensive, and particularly one which can be readily engaged with the wire at one side of the concrete form, and which without disengagement may be employed to draw the wires taut as many times as may be necessary, and immediately thereafter, without disengagement, to twist the wires, and which in twisting them will automatically insure

that the two ends are equally tensioned. More particularly it is an object to provide such a tool which can be readily engaged and disengaged with the wire, and which because of its simplicity and ease of operation will considerably speed up this part of the work of setting up forms, and render it safer for the workman.

It is a further object to provide a tool which is formed of one piece only, whereby all moving parts are eliminated, and the tool is thereby made more rugged and less expensive.

My invention comprises the novel tool, as shown in the accompanying drawing, and as will be more particularly described in this specification and defined by the claims terminating the same.

In the accompanying drawing I have shown my tool in a form which has been found suitable for use, though the precise form thereof may be varied as will appear hereafter.

Figure 1 is an elevation of the tool.

Figure 2 is an elevation of the tool in use, the form being shown in section, illustrating the operation of pulling the wires taut, and Figure 3 is a similar view illustrating the twisting operation. Figure 4 is a fragmentary sectional view, illustrating how the tool will automatically equalize the length and tension of the two ends of the wire. It will be understood that the size of the wire has been shown somewhat exaggeratedly in these views in proportion to the size of the tool and the form parts, hence the operation as illustrated is not strictly in accordance with the true facts.

Preferably the tool is made of a single bar bent to shape. Starting at one end, it comprises a handle 1, which is adapted to be grasped in one hand, as for example the left hand, of the workman. Proceeding thence along the tool toward the opposite end, it is formed with a crank portion 2 offset from the handle 1, to be grasped in the right hand, the two parts 1 and 2 constituting a crank handle, by which the tool may be rotated around the axis defined in general by the handle portion 1. From the crank portion 2 the tool, adjacent the end opposite the handle 1, is preferably bent, first as indicated at 3, to a point within the axis of rotation, and then laterally to one side or the other of such axis, to form a fulcrum portion 4. However, it will be understood that the crank handle 2 might be extended directly to the fulcrum part 4 without the bend indicated at 3. From the fulcrum portion the tool extends substantially diametrically past the axis of rotation, and to the opposite side thereof, and is formed as a spike 5, pointed some-

what so that it may easily enter or be inserted behind a preliminary twist of the ends of the wire. It is also preferably provided with a shoulder 6, lying substantially in the axis of rotation, 5 which limits the extent of insertion of the spike. Preferably the spike 5 and fulcrum 4 are disposed at opposite sides of a diameter through this axis of rotation, that is, each disposed substantially along a line at right angles to the axis 10 of rotation.

The studs 1 and 8, with the form boards 9 and 10, constitute the form which is being erected. A wire 11 is extended through the form 15 around one of the studs, as 8, and past opposite sides of the other stud 7. Here, as seen in Figure 2, the ends may be given one or more preliminary twists, as indicated at 12, by hand, whereupon the spike 5 is inserted behind this twist, as shown in Figures 2 and 4, until the shoulder 6 engages the wires, and the twist will offer sufficient resistance that when the fulcrum 20 4 is placed against the stud 7 the wires may be pulled through and pulled somewhat taut, to take up slack. If the ends are unequal, or unevenly tensioned, or if the spike 5 is not engaged directly behind the twist 12, it is immaterial. Upon pulling through in the manner just described, the two ends will be equally tensioned, as is evident from Figure 4. Immediately thereafter, 25 without any disengagement of the tool it may be rotated about the axis defined by the handle 1, in the manner indicated in Figure 3, the twist being preferably in the opposite direction to the twist 12, forming the twist 13 as seen in Figure 3.

If this does not sufficiently bring the form boards 30 35 together, the tool, without disengagement, may again be brought down with its fulcrum 4 against the stud 7, the wires pulled through in the manner indicated in Figure 2, and the slack thus taken up is again twisted. While the wire is 40 shown of exaggerated size in Figures 2 and 3, in actual practice the twist 13 will not take up so

much space but what the subsequent pulling through operations may be readily accomplished, and if the twist 13 should be of such length as to make this difficult, the tool may be quickly disengaged and reengaged behind the twist 13. 5

As soon as the form boards have been brought close enough together the tool is disengaged by withdrawing the spike from behind the two twists 12 and 13. All these pulling through and twisting operations may be accomplished without disengagement of the tool and in a very rapid manner, yet the disengagement is readily accomplished when the operation is completed. Furthermore, the twist given the wire is a natural twist, so that the wire is not unduly stressed 15 at any given point, and hence has no undue tendency to break or pull loose.

What I claim as my invention is:

1. A tool for twisting and tightening concrete form wires, comprising a crank handle and a 20 spike disposed transversely of the crank's axis, said tool having also a fulcrum formed on the opposite side of such axis from the spike.

2. A tool for twisting and tightening concrete form wires, comprising a crank handle, a spike 25 disposed substantially at a right angle to the crank's axis at one end thereof, and terminating in a wire-engaging shoulder disposed in such axis, and said tool also having a fulcrum formed on the opposite side of such axis from the spike. 30

3. A tool for twisting and tightening concrete form wires, consisting of a bar having a straight end forming a handle, thence extending outwardly and back to the line of said handle, to form a crank for rotation of the tool about an axis defined by said handle, thence extending outwardly from such axis to form a fulcrum adjacent its end opposite the handle, and thence extending across such axis, and formed as a spike for engagement behind a preliminary twist. 35 40
